Primary Examiner — Keli L Hill*Assistant Examiner* — Harold E Blackwell, II(74) *Attorney, Agent, or Firm* — Christopher A. Proskey; BrownWinick Law Firm(57) **CLAIM**

The ornamental design for a shelf pin hole jig, as shown and described.

DESCRIPTION

FIG. 1 is a perspective view of the top, back, and left sides of a shelf pin hole jig showing my new design.

FIG. 2 is a perspective view of the top, front, and left sides of a shelf pin hole jig.

FIG. 3 is a perspective view of the top, front, and right sides of a shelf pin hole jig.

FIG. 4 is a perspective view of the bottom, front, and left sides of the shelf pin hole jig.

FIG. 5 is a perspective view of the bottom, back, and left sides of the shelf pin hole jig.

FIG. 6 is a plan view of the front side of the shelf pin hole jig; and,

FIG. 7 is a plan view of the right side of the shelf pin hole jig.

The dashed lines shown represent the environment and represent unclaimed subject matter and form no part of the claimed design.
